H. Whitney Jr.
Inkstand.

No 8,188. Patented July 1, 1851.

Fig. 1.

Fig. 2.

UNITED STATES PATENT OFFICE.

HENRY WHITNEY, JR., OF CAMBRIDGE, MASSACHUSETTS.

INKSTAND.

Specification of Letters Patent No. 8,188, dated July 1, 1851.

To all whom it may concern:

Be it known that I, HENRY WHITNEY, Jr., of Cambridge, in the county of Middlesex and State of Massachusetts, have invented 5 certain new and useful Improvements in Inkstands, and that the following description, taken in connection with the accompanying drawings hereinafter referred to, forms a full and exact specification of the 10 same wherein I have set forth the nature and principals of my said improvements by which my invention may be distinguished from others of a similar class, together with such parts as I claim and desire to have 15 cured to me by Letters Patent.

The figures of the accompanying plate of drawings represent my improvements.

Figure 1 is a plan of my improved inkstand, and Fig. 2 is a transverse vertical 20 section taken in the plane of the line, A B, Fig. 1.

The distinguishing features of my improvements are the combination of an elastic diaphragm operated by a thumb screw working in a metallic cap fitted over the neck of the fountain of the inkstand with the delivering cup and its tube (extending into said fountain through an independent opening in the top of said fountain); and the 25 providing a sunken area about the opening for the tube of the delivering cup, so that if the ink overflows in said cup, it will be received in said area, and by raising the tube of the cup, be permitted to flow back 30 again into the fountain.

a a a a is the fountain of the inkstand which may be formed of glass or any other desirable material, having a neck or opening at *b b*, through which the elastic dia- 40 phragm *C*, Fig. 2, works up and down. This diaphragm is formed or arranged by tying the center of an india-rubber washer, *d d*, round a groove formed about the metallic button, *e*, the exterior of said circular 45 washer being confined in a groove round the exterior of the metallic socket, *f f*, as shown

in Fig. 2, which socket is formed as shown in said figure, and is fastened with cement at *g* and *h*, about the neck, *b b*, of the fountain, so as to make the whole arrangement 50 air-tight, and leave a space at the center for the vertical play of the diaphragm *C*. A metallic cap, *i i*, is screwed around the lower edge of the socket, *f f*, and has at its center a thumb screw, *k*, the lower part of 55 which is connected to the diaphragm *C*, and moves it up and down, as will be readily understood by inspection of Fig. 2.

The delivering cup, *l*, with its tube, *m*, is formed in the ordinary way, the latter passing through an independent hole in the side of the top of the fountain, and extending nearly to the botom of said fountain; and it will be readily seen that the depressing of the elastic diaphragm about the neck of the 60 fountain by the screw, *k*, will condense the air in the fountain, and make it press the ink into the cup, and by lifting the washer the contrary effect will ensue, and the ink 65 pass back from the cup to the fountain. 70

There is a crescent shaped area, *n n*, about the cup, *l*, which has a rim, *o o*, about it, and whose bottom curves, or inclines toward the hole in which the tube, *m*, of said cup, fits; so that any ink which is overflowed 75 from said cup, may be permitted to pass back into the fountain by merely lifting the tube, *m*.

I do not claim the invention of the elastic diaphragm for inkstands; but 80

I claim my inkstand as a new article of manufacture, in which the following features are for the first time associated, viz:

An elastic diaphragm covered and secured from injury by a metallic cap, and regulated 85 by a screw passing through the cap, and in combination with the diaphragm the funnel stop *l* and waste cup *n*.

HENRY WHITNEY, JR.
